HANDLE LOCK FOR TOOLS

Ernest C. Neal, Chicago, Ill.

Application January 31, 1944, Serial No. 520,401

4 Claims. (Cl. 306—37)

1

This invention relates in general to a device for maintaining a tool head on its handle, and more particularly to a spring clip for securing a tool head, such as a pick axe, a foot adze, a spike maul, a mattock, a grub hoe, and other devices of similar character, and a handle therefor, together in cooperative relation. Tools of the character dealt with herein may be designated collectively as "striking tools," the same being adapted for manual operation in striking impact blows of substantial force upon a workpiece or material. To that end, tools of the class mentioned comprise a relatively heavy striking head carried at the end of a grasping handle, said end being frictionally or wedgingly fitted in a socket which opens through the head.

An object of this invention is to provide compact, safe, simple, efficient and readily applied means for maintaining a tool head of the character stated on its handle in cooperative relation therewith, thus preventing inconvenience and injury incident to a tool head's flying off its handle in use, as the result of wear of associated parts.

A further object of the invention includes the provision of a metal clip which may be manually sprung upon adjacent portions of a tool head and its handle to maintain the tool head and the handle together in cooperative relation.

Another object of the invention is to provide means for securing together in cooperative relation a tool head having an opening extending therethrough and a handle having an end portion received in the opening for frictional engagement with adjacent surfaces of the tool head including a spring collar or yoke having circumferentially spaced end portions and an angulated extension forming a holding lug arranged in angular spaced relation with the spaced end portions so that the collar may be manually sprung upon portions of the tool head, or upon the handle, as the case may be, with a surface of the extension abutting a surface of the other member, that is, the handle, or the tool head, so as to prevent relative displacement of the tool head and the handle, and, in cases where a shim or wedge is used to take up wear of the handle, to maintain the shim or wedge in position.

Other objects of the invention include the provision of novel means in a device of the character stated to facilitate the manual application of such a device to a tool head and handle assembly. Additional objects, advantages and capabilities inherent in the invention will become readily apparent from the description thereof which follows.

2

This invention further resides in the combination, construction and arrangement of parts illustrated in the accompanying drawings, and while there is shown therein preferred embodiments of the invention, it is to be understood that the same are susceptible of modification and change without departing from the spirit of the invention.

The accompanying drawings illustrate a selected embodiment of the invention, and the views therein are as follows:

Fig. 1 is a side elevation of a device embodying the invention applied to a pick axe and handle assembly;

Fig. 2 is an enlarged perspective view of the device shown in Fig. 1 in normal arrangement, prior to the application of the device to a tool head and handle assembly;

Fig. 3 is a sectional view along the line 3—3, with displaced position of the parts as applied to a tool head and handle assembly indicated in dotted lines;

Fig. 4 is an end view of the device looking to the left in Fig. 1;

Fig. 5 is a sectional view along the line 5—5 of Fig. 1;

Fig. 6 is a sectional view along the line 6—6 of Fig. 1;

Fig. 7 is a side view of a modified form of the invention as applied to a foot adze;

Fig. 8 is an end view, looking to the left in Fig. 7;

Fig. 9 is a perspective view of the device shown in Fig. 7 in normal arrangement;

Fig. 10 is a side view of a modified form of the invention as applied to a spike maul;

Fig. 11 is a sectional view along the line 11—11 of Fig. 10.

The particular device herein disclosed for the purpose of illustrating the invention comprises a clip 15 of spring metal including a collar or yoke portion 16 having circumferentially spaced end portions 17 and 18 and an angulated extension 19 arranged in angular spaced relation with the end portions 17 and 18. The extension 19 has an inturned, transversely extending portion 20, forming a preferably integral lug.

The clip 15 may be applied to a pick axe and handle assembly as shown in Fig. 1. In such an assembly the tool head or pick axe 21 is usually provided with a neck portion 22 and a tapering opening 23 extending therethrough. A handle 24, usually of wood, has a correspondingly tapered end portion 25 which is received in the opening 23, the parts usually being forced into frictional engagement in closely interfitting relation

with an end portion 26 of the handle protruding beyond the opening.

Use of the tool usually results in wear of the handle reducing its surface within the opening and permitting interplay between the parts with a resulting tendency of the tool head to become displaced or to slip along the handle. This displacement or slipping can be averted temporarily by driving a shim or wedge into the end of the handle adjacent the tool head but with further use the shim or wedge tends to slip out. Such slipping of the shim or wedge and the tool handle can be effectively averted by applying a clip 15 to the assembly. This is done by manually springing the end portions 17 and 18 apart so that the collar portion 16 will embrace and grippingly engage the outer surface of the neck portion 22 of the tool head and the portion 20 of the angulated extension 19 will abut the end surface 21 of the handle and the corresponding surface of the shim or wedge, if one be used.

In order to facilitate the application of the clip 15 to a tool head assembly, a portion of increased thickness or external bead 28 may be provided on the end portion 17 of the clip in spaced relation with the edge 29 thereof to enable the clip to be hammered into position.

The clip 15 may be made of spring metal of suitable thickness, depending on the size and weight of the tool head, a thickness of $\frac{1}{16}$ inch or $\frac{3}{32}$ inch ordinarily being adequate. The collar portion 16 is preferably tapered to conform with the adjacent surface of the tool head or handle as the case may be. The conformation and arrangement of the parts of the clip are such that the clip will operate to secure the tool head and handle, including a shim or wedge if used, together in cooperative relation notwithstanding additional wear and resulting interplay between the handle and tool head, as the spring quality of the metal will act to cause the clip to conform to the reduced dimensions of the associated parts.

In a modified form of the invention, a metal clip 30 shown in Figs. 7, 8 and 9, as applied to a foot adze 31 and handle 32 assembly, has a collar portion 33, which is generally rectangular in form in contrast with the generally elliptical form 16 shown in Figs. 2 and 3, and end portions 34 and 35, which are substantially alike in configuration and dimensions, each having an in-turned edge 36. This arrangement is necessary due to the generally rectangular sectional configuration of the adjacent portions of the foot adze 31 and handle 32. The spacing of the end portions 34 and 35 and the edges 36 is such that the collar portion may be sprung into position in gripping relation with the adjacent surface of the neck 37. As in the case of the collar portion 16 of the clip 15, the collar portion 33 is tapered to conform with the tapering neck portion 37 of the adze 31. The angulated extension 38 and inturned transversely extending portion 39 are arranged to operate in relation to the end surface 40 of the handle in a manner similar to that of the corresponding portions of the clip 15.

In another modified form of the invention shown in Figs. 10 and 11 as applied to a spike maul, in which the opening 41 in the head 42 and the portion 43 of the handle 44 received in the opening taper in a direction opposite to that of the direction of the taper of the corresponding parts in Figs. 1 to 8 inclusive, the clip 44 is provided with a collar portion arranged to grip an adjacent portion of the handle and the

inturned, transversely extending portion 45 of the angulated extension 46 is arranged to abut an adjacent surface 47 of the head. A wedge 48 may be inserted in the handle (Fig. 10).

Changes may be made in the form, construction and arrangement of the parts without departing from the spirit of the invention, and the right is hereby reserved to make all such changes as fairly fall within the scope of the following claims.

The invention is hereby claimed as follows:

1. A tool head clip for securing a handle, having a shank providing a grasping end and a head mounting end, to a striking tool head, having an opening therethrough for receiving said mounting end, whereby to form a tool assembly having a clip mounting portion at the mounting end of said shank, said clip comprising resilient means forming a collar adapted to contractingly embrace said clip mounting portion, said collar having a lateral opening therein and being expansible to permit said clip mounting portion to enter the collar through said lateral opening in mounting the clip on said mounting portion, and an offset holding lug on said collar in position to overlie the shaft remote side of the tool head and the end of the handle exposed at said remote side.

2. The combination, with a hand striking tool comprising a handle part forming a shank having a grasping and a head mounting end, and a tool head part having a handle receiving opening therethrough and snugly receiving the mounting end of said handle part, whereby the head part is secured on the handle part, one of said parts forming a clip seat adjacent the mounting end and tapering toward the grasping end of said shank, of a tool clip on said clip seat, said clip comprising resilient means forming a tapered collar having a lateral opening therein and contractingly and wedgingly embracing said tapered clip seat and urged thereon, by the resilience of the clip, in a direction toward the grasping end of the handle part, and an offset holding lug on said collar extending in position overlying the handle opening at the shaft remote side of the tool head and the mounting end of the handle part exposed at said remote side;

3. The combination, with a hand striking tool comprising a handle part forming a shank having a grasping end and a head mounting end, and a tool head part having a handle receiving opening therethrough and snugly receiving the mounting end of said handle part, whereby the head part is secured on the handle part, said head part having a neck on one side thereof embracing the mounting end of said shank and forming a clip seat tapering toward the grasping end of said shank, of a tool clip on said clip seat, said clip comprising resilient means forming a tapered collar having a lateral opening therein and contractingly and wedgingly embracing said tapered clip seat and urged thereon by the resilience of the clip, in a direction toward the grasping end of the handle part, and an offset holding lug on said collar extending in position overlying the handle opening at the shaft remote side of the tool head and the mounting end of the handle part exposed at said remote side.

4. The combination, with a hand striking tool comprising a handle part forming a shank having a grasping and a head mounting end, and a tool head part having a handle receiving opening therethrough and snugly receiving the

mounting end of said handle part, whereby the head part is secured on the handle part, one of said parts forming a clip seat adjacent the mounting end, of a tool clip on said clip seat, said clip comprising resilient means forming a collar having a lateral opening therethrough and contractingly and wedgingly embracing said clip seat and urged thereon, by the resilience of the clip, in a direction toward the grasping end of the handle part, and an offset holding lug on said collar extending in position overlying the handle opening at the shaft remote side of the tool head and the mounting end of the handle part exposed at said remote side.
